UNITED STATES PATENT OFFICE.

WILLIAM PAUL RUDKIN, OF OKLAHOMA CITY, OKLAHOMA.

INTERNAL-COMBUSTION ENGINE.

Application filed April 9, 1926. Serial No. 100,921.

The present invention appertains to improvements in internal combustion engines, and has as its primary object to provide a novel construction by means of which steam 5 is utilized in combination with the hydrocarbon fuel as the motive power, whereby economy in operation is effected through a reduction in the consumption of the fuel.

I am aware that it has been proposed heretofore to introduce into an internal combustion engine a limited supply of water vapor from the water system, such vapor reaching the explosion chamber in a finely divided state, and working, if at all, as a moisture constituent, but the present invention is to be 15 distinguished from any method of such character. That is to say, in this invention I employ the heat of combustion to develop from a suitable water supply a quantity of steam 20 which is passed into the explosion chamber in its gaseous state and subsequently compressed by the motor piston, such compression of the gas (steam) producing a superheating thereof. The fuel mixture which is likewise introduced into the engine is fired in the presence of the superheated steam, with the resultant effect of increasing the superheating action and thus adding the expansive force of the steam to the explosive force of the fuel when 25 ignited.

It is further an objective to provide means for automatically controlling the steam supply and correlating the quantity produced with the requirements with respect to the operation 30 of the motor, such that while the steam serves to prevent overheating thereof, as the engine becomes hotter and hotter, a relatively greater amount and pressure of steam is developed in the proportion needed to properly balance 35 the supply with the consumption, whereby the motor will at all times be at the proper operating temperature.

Notable among the results obtained by my 40 novel method and apparatus may be mentioned the elimination of the radiator, now a necessary accessory in water-cooled constructions, and this without a radical change from the present construction of the internal combustion engine; also the ability to utilize a 45 greater heat in the explosion chamber by permitting a much higher compression without premature ignition of the fuel charge and will result in a greater superheating of the steam,—in turn economizing fuel and effect-

ing more perfect vaporization of the fuel mixture. 55

Other objects and advantages of the invention will be hereinafter set forth and the novel features thereof defined by the appended claims. 60

In the accompanying drawings:

Figure 1 is a vertical section of an engine construction embodying my improvements;

Figure 2 is a sectional view of a slightly modified form of the invention; and 65

Figure 3 is an enlarged detail partly in section, showing more clearly the associated fuel and steam supply controls.

Like reference characters designate corresponding parts throughout the several figures of the drawings. 70

Referring to Figure 1 of the drawings, 1 designates the cylinder block of a conventional type of internal combustion motor which is water jacketed as indicated at 2. 75 The detachable engine head 3 which is formed with a water compartment or jacket communicates with the jacket 2 and receives its water supply from the reservoir 4 located at one side of the cylinder block. This reservoir is formed with a neck connection 5 establishing communication with the water jacket 2. The water in the reservoir 4 is maintained at a predetermined level by means of a float valve 6 controlling the outlet of the pipe line 85 7 leading from a main water tank or other suitable source of supply (not shown). A steam pipe 8 leads from the top of the cylinder head into the upper portion of the reservoir 4 which constitutes a steam dome, from 90 which the steam generated passes by way of the pipe 9 to the fuel intake manifold 10 at a point adjacent the carburetor 11. The pipe 9 is provided with a regulator valve 12 and I also dispose at the top of the steam dome 95 a safety or pop valve 4^a to take care of excess pressure whenever such is developed. In order to insure an adequate steam supply I prefer to provide an additional water jacket 13 as a part of the construction of the exhaust 100 manifold 14, water being supplied to such chamber by means of the pipe 15 leading from the base of the reservoir 4. Steam which is developed in this chamber 13 is conducted to the pipe 8 by the pipe 16. 105

In Figure 3 it will be observed that the steam pipe 9 terminates in a nozzle 9' located within the intake passage 10 and this ar-

arrangement is designed to jet the steam into the fuel stream in a regulatable amount under the control of the throttle 17 which operates in conjunction with the fuel throttle 18 through the instrumentality of a suitable control (not shown).

The construction depicted in Figure 2 of the drawings functions in the same manner as that disclosed in Figure 1. The arrangement, however, is somewhat different. The engine head 3' in this form is provided with the steam dome 3'' at the top thereof and the float valve 6' is mounted within the cylinder head, maintaining the proper level of the water supply from the reservoir 4'. A connection 8' is made between the steam dome and the top of the reservoir 4' so as to maintain in the latter a pressure corresponding to the pressure in the steam dome, for reasons obvious to those skilled in the art to which this invention relates.

The water supply is led from the reservoir 4' to a float chamber 19 by the pipe 20 and from this chamber a nozzle 21 extending within the steam nozzle 9' enters the intake manifold 10. In this manner a certain amount of moisture under the control of the valve 22 is introduced with the steam which latter acts to atomize the water and intermix it with the atomized fuel. The amount of moisture is relatively small so as to eliminate any likelihood of interfering with the operation of the igniter.

An important feature of this construction resides in the provision of a pressure regulating valve 23 in the pipe line 9, this being capable of adjustment according to the variations in the grades of fuel which may be employed in the operation of this engine construction. By the regulation or setting of this valve the pressure in the steam dome or chamber 3'' may be controlled, the greater the pressure the higher the boiling point for the water contained therein. Obviously, therefore, the heat of the engine is subject to control by the adjustment of this valve and this is particularly important in the regulation of the heat of the engine for using oils of different grades.

Having thus described my invention, what I claim as new and desire to secure by Letters Patent of the United States is:

1. In an internal combustion engine of the class described, a cylinder, a water jacket therefor, a water supply communicating therewith, a steam chamber, means for introducing steam therefrom into the cylinder, and moisture supplying means associated with the last named means operative to introduce into the cylinder a regulatable amount of moisture under the control of the steam.

2. The method of operating an internal combustion engine which comprises utilizing the heat of explosion to generate a supply of steam, conveying said steam to the firing chamber of the engine, introducing moisture into the firing chamber under the control of the steam and introducing a supply of fuel into the firing chamber in the presence of the steam and moisture, and firing the charge in the presence of said steam and moisture.

3. In an internal combustion engine of the class described, a cylinder, a water jacket therefor, means for feeding and regulating a fuel charge to the cylinder, a steam chamber, means for introducing steam therefrom into the cylinder and controlling the supply thereof, and moisture supply means associated with the last mentioned means operative to introduce into the cylinder a regulatable amount of moisture under the control of the steam.

4. The method of operating an internal combustion engine which comprises utilizing the heat of explosion to generate a supply of steam, conveying said steam to the firing chamber of the engine, introducing moisture into the firing chamber under control of the steam and introducing a supply of fuel into the firing chamber in the presence of the steam and moisture, compressing the fuel charge, steam and moisture within the cylinder, and firing the charge in the presence of the compressed steam and moisture.

In testimony whereof I affix my signature.

WILLIAM PAUL RUDKIN.
